(57) **CLAIM**

We claim the ornamental design for a graphical user interface embodied in a display panel, as shown and described.

DESCRIPTION

FIG. 1 illustrates a first state of a graphical user interface embodied in a display panel according to the invention.

FIG. 2 illustrates a second state of the graphical user interface of FIG. 1; and,

FIG. 3 illustrates a third state of the graphical user interface of FIG. 1.

The appearance of the transitional image sequentially transitions between the images shown in FIGS. 1-3. The process or period in which one image transitions to another image forms no part of the claimed design.

The broken lines in the drawings are for illustrative purposes and form no part of the claimed design. The accompanying figures, FIGS. 1-3, depict three states of the graphical user interface of the present invention embodied in a display panel.

1 Claim, 3 Drawing Sheets

FIG. 1

FIG. 2

FIG. 3
